UNITED STATES PATENT OFFICE.

WALTER L. SCHULTZ, OF CHICAGO, ILLINOIS.

BOTTLE CAP.

Application filed May 16, 1922. Serial No. 561,424.

To all whom it may concern:

Be it known that I, WALTER L. SCHULTZ, a citizen of the United States, residing at Chicago, in the county of Cook and State 5 of Illinois, have invented certain new and useful Improvements in Bottle Caps, of which the following is a specification.

This invention has reference to improvements in bottle caps designed particularly 10 for closing milk bottles, although adapted for other like purposes, and therefore not confined to milk bottles alone.

Like milk bottles generally, the cap is made of some cheap material which may be 15 readily manufactured in large quantities and at small expense since such bottle caps are used but once and are then discarded.

In order to prevent the bottle cap from representing too large a proportion of the 20 cost of the closure with relation to the value of the contents of the bottle and at the same time to provide a bottle cap which shall be particularly efficient in use, the cap must be very cheaply made and must very effectively 25 seal the bottle, especially where the contents of the bottle consists of milk.

Ordinarily, bottle caps are made of a single thickness of paste board or cardboard, which will not prevent access of ferment 30 germs to the milk contained in the bottle, for more than a very short period of time.

In order to prevent ready access of such ferment germs, the present invention contemplates the employment of a plurality of 35 layers of cardboard in face to face relation and cemented in such relation one to the other.

One of the cardboard disks is of full 40 circular contour to fit snugly into the mouth of the bottle. The next disk is of only partially circular contour and is considerably smaller in area than the first disk, and the peripheral edge of the second disk coincides with a portion of the peripheral edge 45 of the first disk and then terminates in a tab projecting through a slit in a third disk, which third disk is of full circular contour, while the tab is accessible on that face of the disk, through which it extends, remote 50 from the full circular disk.

By the employment of three components of the bottle or jar stopper, access of ferment germs to the interior of the bottle is practically impossible, and milk inclosed in 55 the bottle and protected by a triple-wall stopper or cap is practically proof from con-

tamination and will "keep" for a far longer period than is usually the case with milk bottles protected by a single-lamina stopper.

The invention will be best understood 60 from a consideration of the following detailed description taken in connection with the accompanying drawings forming part of this specification with the understanding that the invention is not confined to any 65 strict conformity with the showing of the drawing, but may be changed and modified so long as such changes and modifications mark no material departure from the salient features of the invention as expressed in the 70 appended claims.

In the drawings:—

Figure 1 is a perspective view of the upper 75 end of a milk bottle equipped with the invention.

Fig. 2 is a plan view of the bottle stopper separate from the bottle.

Fig. 3 is a section on the line 3—3 of Fig. 2.

Fig. 4 is a plan view of one of the 80 elements of the stopper.

Fig. 5 is a plan view of a second element of the stopper.

Fig. 6 is a plan view of a third element 85 of the stopper, such three elements, shown separately in Figs. 4, 5 and 6, appearing in the section of Fig. 3.

Referring to the drawings, there is shown the upper end of a milk bottle in Fig. 1, such milk bottle being of ordinary construction and provided with a mouth 2.

The milk bottle 1, as shown in Fig. 1, may be of ordinary construction except that the mouth 2 may be of greater depth than usual because of the increased depth or 90 thickness of the stopper, which latter appears complete at 3 in Fig. 3.

The bottle stopper or cap 3 comprises three separate elements 4, 5 and 6, respectively, and shown separately in Figs. 4, 5 and 6, independent of the others.

The element 4 of the stopper is in the form of a full circle and contains near one edge a slit or slot 7 in chord relation to one side of the stopper element 4.

The stopper element 5 is of but partially circular contour, having a portion of its periphery defining a full circle and the remainder of its periphery, indicated at 8, of sharper curvature so that the area of the 110 section 5 is less than that of either of the sections 4 or 6, both of which define full cir-

cles. Extending centrally from the intermediate portions of the section 5 from the approaching side 8 is a tab 9 of a width which may correspond to the customary manipulating tabs of milk bottle stoppers. The tab 9 extending through the slot 7 at an angle to the surface of the disk 4 will naturally trend away from the outer face of the disk 4 and so constantly assume an accessible position so that the tab may be very readily grasped by the hand of the operator and present no difficulty to being lifted from its seat in the mouth of the bottle, although at all times tending to lie quite flat in the mouth of the bottle, for the tab may be long enough to engage the mouth of the bottle and thus be grasped without difficulty.

To assemble the bottle stopper, the stopper element 5 has the tab 9 passed through the slot 7 with the two tabs 4 and 5 united by a layer of glue or cement so that the peripheral portions of the two disks are in coincidence.

Having assembled the two disk members 4 and 5, the third disk member 6 is applied onto the disk member 5 so as to overlie the disk member 4, being glued or cemented thereto. The disk member 6 thereupon encloses the disk member 5 and the three disks are firmly united as one member.

By this means, the bottle stopper or cap is made of a triple member with intervening layers of glue or cement and produces a structure which is amply stiff or sturdy for the purposes of the invention.

One objection to bottle caps or stoppers with single manipulating tabs, is the fact that the tabs often break off, and this objec-

tion is in a large measure overcome by this invention.

What is claimed is:—

1. A cap for milk bottles comprising a plurality of paper disks, of which spaced ones conform in shape and size to the mouth of the bottle, and another one is of less than circular shape and smaller than the mouth of the bottle and provided with a tongue traversing a slot through the outermost one of the disks.

2. A cap or stopper for milk bottles comprising a plurality of fiber disks in superposed order, with spaced ones of the disks corresponding in size to the mouth of the bottle and an intermediate disk located between the other disks, and the last named disk having a tab or finger projecting from and formed in one piece therewith and one of the disks having a thin slot therethrough in chord relation to the perimeter of the disk to pass the tab or finger.

3. A cap or stopper for milk bottles comprising a plurality of fiber disks united in superposed order, with the outer ones of the disks conforming in size and position to each other and to the size of the mouth of the bottle and an intermediate one of the disks being of less area than the other disks and provided with a tab or tongue projecting from a slot through one of the first named disks in chord relation to the edge of the disk, and the several disks being glued or cemented together face to face to register in the bottle mouth.

In testimony whereof, I affix my signature hereto.

WALTER L. SCHULTZ.
